Primary Examiner — T. Chase Nelson*Assistant Examiner* — Kathleen M Sims(74) *Attorney, Agent, or Firm* — Crose Law LLC; Bradley D. Crose(57) **CLAIM**

The ornamental design for a free-standing pond, as shown and described.

DESCRIPTION

FIG. 1 is a perspective view of a free-standing pond, from a third of the way around between the front and the right hand side, illustrating the new, original, and ornamental design; FIG. 2 is a perspective view of the free-standing pond, from two thirds of the way around between the front and the right hand side, illustrating the new, original, and ornamental design;

FIG. 3 is a perspective view of the free-standing pond, from above, illustrating the new, original, and ornamental design; FIG. 4 is a top plan view of the free-standing pond, illustrating the new, original, and ornamental design;

FIG. 5 is a front elevation view of the free-standing pond, illustrating the new, original, and ornamental design; FIG. 6 is a right side elevation view, the left side being a reverse image thereof, of the free-standing pond, illustrating the new, original, and ornamental design; and,

FIG. 7 is a rear elevation view of the free-standing pond, illustrating the new, original, and ornamental design.
The broken lines shown in the drawings are included for the purpose of illustrating environmental structure and form no part of the claimed design.
